BAG CLAMPING DEVICE

Peter Hannah, Yonkers, N. Y.

Application February 23, 1938, Serial No. 191,883

11 Claims. (Cl. 248—101)

The present invention relates to automatic weighing and dispensing machinery and it particularly relates to a bag or flexible container filling machine.

Although the present invention has broad application to all types of machines where it is desired to dispense, segregate or weigh out predetermined portions of pulverized, powdered or granulated materials or of grain or particle materials, such as wheat, oats and corn, it will be particularly described in connection with its application to weighing machinery designed to weigh out large quantities of powdered or finely divided materials, such as fertilizers, in paper, cloth or other bags.

In machinery of this character, it is often desirable to provide some means of firmly and satisfactorily grasping the top of the bag-like container, whether it be of cloth or paper, so that the material being dispensed, segregated or weighed, may be readily fed into said bag-like container, without collapse of the container and with assurance that the container will not be deformed or misshapen and may be readily passed through a sewing machine after filling.

Ordinarily the bags when of paper or burlap are usually flattened in one direction so that they will be readily engaged and operated upon by said sewing machine after the bag has been filled. However, where a cable is utilized to grab the top of the bag during the filling thereof, this cable will often crush or crumple the pleats and wrinkle the top of the bag so that it is not most readily possible to pass the bag through a sewing machine without uneven sewing or stitching at the upper portion of the bag.

It is therefore among the objects of the present invention to provide an improved bag holding mechanism which may be readily employed in weighing, dispensing or segregating machines of the character above described, according to which the bag will be firmly grasped during the filling operation and at the same time will not be deformed, wrinkled nor will its pleats be changed, with the result that the bag, after filling with the segregated or predetermined charge, may be readily passed through a sewing machine to give an even and satisfactory closure.

It is among the further objects of the present invention to provide an improved bag holding mechanism of the character described which readily adjusts itself to various sizes of bags and which would readily accommodate itself to the slack in various shapes and sizes of bags for different weights of materials without the neces-

sity of utilizing a cable and without the necessity of utilizing a different sized or shaped bag holder for each different size or shape of bag.

In machines of the type which are designed to weigh out large quantities of materials, varying from 50 to 150 lbs. more or less, it is often desired to strike a trial balance during the course of the weighing or segregating operation, say for every fifth or tenth bag and according to machines now in use, it is necessary to drag these heavy bags after they have been filled by the automatic weighing machine to a floor scale to test the weight and to determine whether the weighing machine is in correct adjustment. This not only slows up the operation, but in addition puts a heavy manual burden upon the operator of the machine.

Further objects will be obvious or will appear during the course of the following specification.

20 In accomplishing the above objects in accordance to one embodiment of the present invention, the weighing pan is preferably provided with a spout around which are positioned two movable clamping jaws which are manually and automatically adjustable, said jaws taking the form of segments and in the preferred form being grooved and cooperating with ridged members on the spout of the dispensing device. These clamping jaws are pivotally mounted upon swinging arms, which arms are in turn pivotally mounted at the rear of the spout. A coil spring is provided to draw the arms and the pivotally mounted jaws apart. The jaw members carried on the arms may be moved together to clamp a bag upon said spout by a lever, which may be actuated to initiate operation of the weighing or other dispensing or segregating machines.

25 The arms are preferably provided with extensions and operating means extending forwardly of the spout and which are designed to be pressed together to hold any slack in the bag and prevent it from dropping during the filling of the bag.

The jaws are preferably so positioned in cooperation with the slack holding elements that the 30 pleats of the bag are not destroyed while the bag is being held in position and so that the bag may be readily passed through a sewing machine after it has been filled and the proper quantity has been weighed out.

35 In normal operation, the material to be weighed will be fed through a downwardly converging hopper and through the spout into the clamped bag. At the bottom of the hopper are two closure gates. As the bag has almost received the correct weight the lowering of the

forward ends of the scale beams carrying the clamped bag will result in first closing the main gate, decreasing the stream of material flowing into the bag, and then, when the correct weight has been received, in closing a secondary gate, cutting off the stream of material, due allowance, of course, being made for the column in air.

As soon as this correct weight has been fed into the bag or other container the filled bag may be released locking the scale beam and a new bag may be placed in position on the spout.

When it is desired to check the amount of material in the bag and determine whether the scale is properly functioning to weigh out the predetermined quantity of material, an arrangement is provided in one preferred embodiment of the present invention to disconnect the gates from the scale beam and permit the scale to balance with the bag in position. In the preferred construction, this is accomplished by having a series of unlatching devices, at least one at each side of the scale, which when actuated will permit the scale to swing freely, determining the balance and giving assurance to the operator that the machine is properly functioning to weigh out the desired quantities of material.

It is also usually desirable to provide an indicator to enable exact determination of the balance of the scale, which indicator may consist of a ruler or scale positioned on the machine frame and a pointer fixed to the swinging element.

In the drawings, to which reference is had for the showing of one preferred embodiment of the invention, but to which the invention is by no means restricted, said drawings merely illustrating and not restricting the invention:

Fig. 1 is a front view of the spout and hopper construction, showing the holding jaws and the latching arrangements designed respectively to hold the bag being filled, and permit balancing of the weighing device when it is to be checked, the bag holding jaws being shown in closed position.

Fig. 2 is a side view upon the line 2—2 of Fig. 1, showing the holding jaws when clamped to hold a bag in position and also showing the right hand balancing latch in solid lines and the left hand balancing latch in dotted lines.

Fig. 3 is a side view similar to Fig. 2 with hopper gates closed, illustrating the position of said jaws after said bag is discharged and when a new bag is to be placed upon the discharge spout.

Fig. 4 is a fragmentary side sectional view upon a somewhat enlarged scale upon the line 4—4 of Fig. 3, showing the right hand balancing latch construction when in normal operating position.

Fig. 5 is a fragmentary side sectional view similar to Fig. 4, showing the right hand balancing latch construction when it has been actuated to permit of testing the balance of the scale.

Fig. 6 is a fragmentary side sectional view upon the line 6—6 of Fig. 1, and upon a somewhat enlarged scale showing the latching arrangement for the bag holding jaws.

Fig. 7 is a side perspective view of the bag holding jaw latching arrangement of Fig. 6 from the other side, Figs. 6 and 7 showing the position of the arrangement when the jaws are clamped to grasp the bag upon the spout.

Fig. 8 is a fragmentary side view in partial section upon the line 8—8 of Fig. 1, showing the left hand balancing latch construction.

Fig. 9 is a front view upon the line 9—9 of Fig. 8.

Fig. 10 is a transverse sectional view upon the line 10—10 of Fig. 1, showing the jaws in closed position in solid lines and in open position in dot and dash lines.

Fig. 11 is a fragmentary transverse sectional view upon the line 11—11 of Fig. 10 showing the engaging structure of the gripping jaws and the holding members upon the side of the spout.

Fig. 12 is a front view of the slack holding elements upon the line 12—12 of Fig. 10, upon a somewhat enlarged scale.

Figs. 13 and 14 show an alternative construction at the rear of the spout, Fig. 13 being a fragmentary top view and Fig. 14 being a transverse sectional view upon the line 14—14 of Fig. 13.

Figs. 15 and 16 illustrate an alternative clamping jaw construction, Fig. 15 being a top view in fragmentary section and Fig. 16 being a side view, and

Fig. 17 is a transverse sectional view of an alternative connecting link construction for said clamping arms.

Referring to Figs. 1 to 3 and 8, the arrangement is provided with a frame A, with the balancing arms M and N, with the weight carrier structure C, with the feeding hopper D, with the spout E, with the bag holding structure F, with the slack holder G, with the right hand balance latching construction H and with the left hand balance latching construction I, and with the jaw latching construction J.

As shown in Figs. 1 to 3, the frame A is provided with longitudinal frame elements 20 and 21, respectively, at the right and left hand sides thereof, which elements are supported by the vertical tube elements or columns 22 and 23. The elements 20 and 21 carry the frame 24 and 25, which form part of the transverse structure 26 to which the hopper D is attached. The anvils 25a, only the left one being shown (Figs. 1 and 9) limit the travel of the beam below the poised position.

The hopper D as shown in Figs. 2, 3 and 8 has the vertical front wall 27, the inclined rear 28 and the inclined side walls 29, the entire hopper being designed to be connected to a supply of material (for example, fertilizer) which is fed through and passes therefrom into the spout structure E.

Although one closing gate might be employed, the present invention will be illustratively described in connection with a double gate construction. Pivotally connected to the bottom of the hopper D are the two closing gates or valves K and L, the closing gate K being arranged first to close and principally cut off the feed when the desired quantity has substantially been weighed out or segregated and the closing gate L being designed to cut off the dribble feed resulting thereafter when finally the exact weight has been arrived at.

As shown in Fig. 1 the closing gate consists of an elongated structure 30 having a lip 31, carrying ear 32 which is provided with an adjusting screw 33. The upward movement of the gate K is also stopped by the rubber plug 34 which fits into the holder 35, said holder being attached by a bracket 36 and the bolts 37 to the front plate 27 of the hopper D.

The sides of the gate K are provided with the arms 38 which are pivotally mounted at 39 upon the sides of the hopper element D. The sides of the arms are turned upward to form lips 40, as

is indicated in Figs. 2 and 3. When the gate K is closed it will closely fit against the front open bottom portion 41 of the hopper D.

The dribble gate L is provided with the faces 13 and 14 which respectively are designed to close against the back 15 and the lower edge 16 of the hopper D (see particularly Figs. 2 and 3).

The dribble gate L at its forward end 17 encloses the rear end 18 of the main gate K, when the gates are closed as indicated at Figs. 3 and 8. The side arms 19 of the dribble gate L are pivotally mounted at 20 upon the side walls 29 of the hopper D.

The balancing structure includes the right and left hand beam arms M and N (see Figs. 2, 3 and 8) which arms are connected by a cross-rod 55. Each arm is provided with a knife edge 56, which fits in a groove 57 in the support element 58 set in upwardly extending boss 58a attached to the frame 24 and 25.

The rear ends 59 of the balancing arms are provided with the knife edges 60, upon which fit the heads 61 of the swinging structure C, said structure C having the side members 62 and the cross bar 63, which supports the slotted weights 64 as best indicated in Fig. 2. The front downwardly extending portions 65 and 66 of the arms M and N respectively (see Figs. 2, 3 and 8) are provided with the knife edges 67 and 68, upon which knife edges are suspended the heads 69 of the arms 70 and 71, as best shown in Fig. 1. The arms 70 and 71 extend inwardly at 72 toward the downwardly converging spout structure E.

It is thus seen that the spout structure E together with the jaw clamping members F and G are suspended from the front side of the balancing arms M and N while the weight structure C is suspended from the rear end of the arms M and N.

The spout structure E includes the converging column member 95 (see Fig. 10) provided with a flat front face plate 96, to which are attached the bearing brackets 97 having bolted connections at 98 to said flat front plate 96. In the brackets 97 bear the vertical shaft elements 99, to the upper ends of which are connected beveled gears 100 and to the lower ends of which are connected the arms 101. The arms 101, at their forward ends are connected to the threaded bolts 102 which are threaded into the hexagonal adjustment sleeves 104. The take-up or adjustment sleeves 104 in turn are connected to the threaded bolts 103. The lock nuts 105 enable said sleeves to be fixed in any desired adjusted position.

The ends of the threaded bolt elements 102 and 103 are turned as indicated at 106 and 107 on Fig. 1, into rounds, which rounds are held below the washers 108 and 109 by the screws 110 and 111 (see Fig. 1). The screws 110 are threaded into upwardly projecting posts on the front ends 112 of the arms 101 and the screws 111 into the cylindrical projection 113 of the semi-circular arm elements 114 of the bag gripping structure F.

The circular arms 114, as shown in Fig. 10, carry the clamping jaws 115 and the arms are provided with rear upwardly curved extensions 116, pivotally mounted at the rear upon the pivot 117, which in turn is mounted upon the bracket 118. The bracket 118, as shown in Fig. 2, is connected by the arm 119 to the flange 120 which is bolted at 121 to the spout element E.

The arms 114, with their jaws 115 are normally held away from each other, in the position as indicated in dot and dash lines in Fig. 10, by the spring 122, the ends of which connect to the pins 75

123 upon the lugs 124, extending outwardly from the rear extensions 116 of the semi-circular arms 114. The rear portion of the spring is received in the recess 125 in the rear of the bracket 118. 5 When the arms 114, and the jaws 115 carried thereby, are moved toward the spout E the spring 122 is tensioned in being moved from the dot and dash position to the solid line position, as shown in Fig. 10, thus biasing the arms 114 so that they will tend to separate from said spout element E.

As indicated best in Fig. 11, the jaw elements 115 are provided with V-shaped grooves 126 at their inside edges and with U-shaped slots 127 at their rear sides, which slots receive the curved arms 114. The middle portion of the jaw element is provided with the circular extension 128 (see Figs. 10 and 11) which receives the pivot pin 129 extending through said extension 128 and 20 said arm 114. The split pin elements 130 indicated upon Fig. 11 hold the pin 129 in position.

The upper and lower sides of the slots 127 are normally spaced away from the upper and lower sides of the arm 114 and the inner edge 131 (see 25 Fig. 10) only projects slightly into said slot 127, being substantially spaced from the bottom of said slot as indicated at 132 in Fig. 10. As a result, the jaws 115 may swing upon their pivots 129 relatively to the arms 114 and adjust themselves when they are clamped home in the solid line position, as indicated in Fig. 10. The pads 133, which may be cast integrally with the arms 114 preferably contact with the upper and lower faces of the grooves 127 to prevent canting of the pivoted jaw members 115.

The V-shaped grooves 126 on the inside faces of the jaw 115 cooperate with the V-shaped projections 134 on the rings 135, the inner ends of 40 which rings are shaped to fit into the V-shaped grooves 136 on the lower portion 137 of the spout element E (see Fig. 11).

When the jaws 115 are clamped against the rails or rings 135, the bag indicated at 138 in Fig. 10 will be closely clamped in the space between the elements 126 and 134 of Fig. 11 and will be held over the length of the jaws 115, the jaws 115 automatically adjusting themselves to the thickness of the upper part of the bag on the rails or rings 135.

50. The forward portion or excess portion 139 of the bag (see Figs. 10 and 12) will then be gripped between the V-shaped projection 140 and the V-shaped groove 141 formed upon the front portions 112 of the arms 101, said V-shaped projections and grooves being formed on each arm 101, so that the arms will be all of the same shape and will be interchangeable.

55. The shafts 99, which actuate the arms 101 and the jaws 115 through the levers 114, are in turn operated from the shaft 142 (see Fig. 1), which carries the beveled gears 143 meshing with the beveled gears 100 fixed to the upper end of said shafts 99.

The shaft 142 bears in the ears 144 which are formed on the front 96 of the spout E. At its right hand end, as shown in Fig. 1, it passes through the bored hub 145 (see also Fig. 6) of the lever 146. The lever 146, as shown in Fig. 6, is keyed to the shaft 142 and is provided with a slot 147 through which projects the bolt 148 having the lock nut 149. The bolt 148 is connected to the lever 150 and the two levers 146 and 150 may be locked or clamped in adjusted position by said nut 149 and bolt 148. The position of said lever 150 may be adjusted by the

screw 152, which extends from the flange 153 and is fixed in position by the lock nut 154.

The lever 150 is also carried on the shaft 142 and moves rigidly therewith in view of its connection to the quadrant 146. The end of the lever 150 carries the roller 155, which roller in the position shown in Fig. 7 fits in the recess 156 in the depending arm 157 of the lever 158, the lower end of said lever, being beveled or inclined, as indicated at 159 to permit of ready movement of the roller 155 into the position as shown in Fig. 7.

The upper end of the lever, as shown in Fig. 7, is provided with the clevis 160 which is pivotally mounted upon the outward projection 161 by the pivot pin 162. The lever 150 is also provided with an integral wedge-shape element 163 carried by the collar 164 on the shaft 142. The rear side of the wedge 163 is stopped by the projection 165 on the clevis 166 of the handle member 167. It will be noted that said clevis has the eyes 168, bearing upon the shaft 142 and that one of said clevises has a hooked projection 169 to cooperate with the pin 170 on the depending arm 171 of the lever 158.

The outer part of the lever 167 is turned as indicated at 172 (see Fig. 1) and it ends in a ball 173, which affords a convenient means of gripping the lever. The end of the shaft 142 is threaded as indicated at 174 and receives a nut 175, against which reacts the coil spring 176, the other end of said coil spring reacting against the face 177 of the clevis 166. The clevis 166 is also provided with an extension 178 (see Fig. 7) which carries a roller 179, held in position by the bolt element 180.

The roller 179, which moves with the spout structure E, is designed to cooperate with the foot element 181 (see Fig. 2) which is bolted at 182 to the frame 20. The coil spring 183 (see Figs. 2 and 3) is connected at one end to the pin 184 on the lever 157 and at its other end, it is connected to an eye 185 (see Figs. 2 and 3), which connects with the threaded element 186 adjustably held by the wing nuts 187 in the ear 188 attached to the hopper element E.

The clevis 166 encloses the eye 189 (see Fig. 1) which in turn is positioned at the lower end of the arm 190, extending downwardly from the side elements 72 suspending the structure E. The structure E is also provided with the side arms 191, which connect with the arms 192 and 193 (see Figs. 1 and 2). The lower ends of the arms 192 and 193 carry the eyes 194, which receive the bolts 195. To said bolts 195 are connected the forward ends of the links 196. The links 196 at their rear ends are pivotally mounted by the bolts 197 on the lower ends of the downwardly extending frame members 198, the upper ends of which are connected to the beams 20 and 21, as shown best in Figs. 2 and 3.

In the operation of the structure, so far described, before a bag is placed upon the lower end of the structure E, or after a bag has been removed therefrom, the lever 167 will be in position as indicated in Fig. 3.

The empty bag is then placed upon the extension or expander 199 with its upper edge substantially above the jaws 115 and the ring 134 (see Figs. 10 and 11). At this time, the jaws 115 will be in position indicated by the dot and dash lines in Fig. 10, and the structure E, together with the depending arms K and the beam members M and N will be locked against oscil-

lation by contact of the roller 179 against the plate or bar 181 as shown in Fig. 3.

Then the lever 167 moves from the position of Fig. 3 to the position of Fig. 2. This will move the roller 179 from its locking position in respect to the bar 181, releasing the structure E and the scale beams M and N, and permitting them to swing freely. At the same time the extension 165 (see Fig. 7) will contact the sector 163 and will cause the lever 150 to be elevated from the position of Fig. 3 to the position of Fig. 2. During this movement the roller 155 will move across the beveled edge 159 of the lever 158 and then will lock in the recess 156 on the inside face of the curved lever 158 (see Figs. 6 and 7).

The shaft 142, being fixed in respect to the elements 150 and 163, will turn the beveled gears 143. These beveled gears 143 in turn will cause rotation of the beveled gears 100 and actuate the shafts 99 to move the arms 101 from the dot and dash position of Fig. 10 to the solid line position.

During this operation, the spring 122 will be extended from the dot and dash to the solid line position (see Fig. 10), the jaws 115 will be clamped against the ring 135 and finally the forward ends of the levers 101 will come together with the excess 139 being gripped between the projection 140 and the recess 141, as also shown in Fig. 12.

If the bag is pointed at its ends so as to be readily run through a sewing machine, the rear end should be at the position 138 indicated in Fig. 10 and the forward end should be at the position 139 with the result that the bag will not be crumpled or ruffled after the weighing operation.

The length of the arms 101 is such in respect to the arms 114-116 that the jaws 115 will first be clamped firmly against the ring elements 135 before the forward ends of the arms 101 are forced into the position as indicated in Fig. 12.

When the bag has been clamped in position, the structure E, suspended on the arms 72 will be free to move upwardly, the weights 64 overcoming the weight of the structures E and 72. The beams M, N and the spout E will move into the position as shown in Fig. 2. At the same time the gates K and L will be open, permitting the material to flow from the hopper D into the interior of the structure E and thence into the bag.

In a manner to be described the gate K will first close as the structure E descends, permitting only a dribble feed, which will continue until the bag has received the proper weight except for the flowing column. Then the gate L will also close cutting off further feed from the spout D into the bag carrying structure E. Then the arm 167 may be moved from the position of Fig. 2 to the position of Fig. 3 to open the arms 101 and the jaws 115 and release the bag. This bag may then be fed into an adjacent sewing machine, since its top will be substantially flat and elongated.

The adjustment 104 on the threaded links 102 and 103 functions to regulate the tension of the jaws F on the top of the bag so that it will be sufficient to hold the bag in place without slipping. The adjustment 104 permits variation in the position of the jaws 115 and 140, 141.

During the weighing operation the links 196 by reason of their pivotal connection to the ele-

ments 183 and 198, will prevent the structure E from swinging backwardly and forwardly.

The gates or closure members K and L are actuated by the scale beams M and N. When the spout E descends they will be permitted to close under their own weight, the gate K closing first and when the spout E ascends, they will be opened by levers actuated by the forward ends of the scale beams M and N.

The dribble gate L is provided with an upstanding arm 81 connected to one of the said flanges 79 (see Figs. 2 to 4). The arm 81, as best shown in Fig. 4, is provided with a latch structure 82 pivotally mounted on the arm by the bolt 210, the lower end of which latch cooperates with a roller 83 carried by the bar 84. The bar 84 is connected by the bolts 54 to the forward end of the scale beam M.

In the construction of Fig. 4, when the scale beam M moves upwardly at its forward end, as when an unfilled bag is attached to the device F, the roller will strike the latch 82 and move the arm 81 from the position as shown in Fig. 3 to the position as shown in Fig. 2, opening the gate L. It is only when the forward end of the scale beam M has descended to its lowermost position, as shown in Fig. 3, that the gate L will be permitted to close, cutting off the dribble feed from the hopper D.

The gate K is controlled on the other side of the scale, as best indicated in Figs. 1, 8 and 9. The side flange 38 of the gate K is provided with an upstanding arm 49a which has a cylindrical extension 41a at its upper portion slotted at 42 (see particularly Fig. 8). In the slot there is pivotally mounted the latch element 43 by the bolt 45. The latch 43 has a handle 44 and a downwardly extending leg 46 with a foot 47. The foot 47 is arranged to contact with the cooperating foot 49 mounted at 48 upon the scale beam N (see particularly Fig. 9).

The weight 50 is attached to the plate 52 by screw element 51 received in the slot 50a. The weight 50 tends to counterbalance the gate K and tends to hold said gate slightly open. The weight 50, together with the plate 52 is connected by the arm 53 to the gate extensions 38 and 40a. The weight 50 exerts a downward pressure on the scale beam and its load, to depress it to dribble position earlier than the load flowing in would normally depress it, so that when it arrives at dribble position, there is yet some material required to complete the load in the sack. The further to the right the weight 50 is moved (Fig. 8), the earlier the beams arrive at dribble position and the longer the dribble stream runs. This slows the cycle. Reversing the procedure, moving weight 50 to the left, speeds up the weighing time by causing the feed to remain longer on the main or preliminary stream.

As the forward end of the scale beam N elevates it will open the gate K, the said opening of the gate K taking place after the opening of the gate L in the manner previously described. At the same time when the forward ends of the scale beams M and N are lowered, the gate K will close before the gate L.

When the forward ends of the beams M and N move to their lowermost position, the bag or receptacle will have received substantially its complete weight and the gates K and L will cut off further feed of material. At this time the column in air will complete the weight of material to be placed in the bag.

Thus it is apparent that scale beams M and

N are at all times arranged to actuate the gates K and L to open them when the front ends of the scale beams move upwardly and it would not be desirable to have the forward ends of the beams swing freely with a filled bag. It is desirable, however, in case a trial balance is to be made, to provide an arrangement to disengage said scale beams M and N from said gates K and L, whereby the filled bag may be permitted to swing freely in balance with the weights 64.

When it is desired to test the balancing condition of the scale without removing the bag from the structure E, it is possible to utilize the latching structure H, as shown in Figs. 4 and 5, and the latching structure I, as shown in Figs. 8 and 9, which will disconnect the beams M and N from the gates K and L, permitting the structure E, with the attached bag containing the predetermined amount of material to swing freely in balance with the weights 64.

Referring first to the latching structure H, the element 82 fits in the groove 211 and its inside face normally lies flat against the outside face of the arm 212, below said groove as indicated at 213. The pin 214 carried by the element 82 fits in a recess 215. The lower end of said latch 82 is flattened as indicated at 216a to form a contact face for said roller 83.

The upper end of said depending member 82 is provided with an extension 216, which is provided with a beveled lower edge 217, under which, in balancing position as indicated in Fig. 3, extends the finger 218, connected by bolts 220 at its lower end to the beam 221, which beam 221 is in turn connected to the beam 222 by the offset portion 223 (see Fig. 4). The beam 222 is pivotally mounted at 224 on the standard 225, connected by bolts 226 on the longitudinal frame member 20. The rear end of the element 222 is provided with a downwardly turned portion 225a, which contacts with the frame member 20 to limit movement thereof.

The forward end of the beam 221 is pivotally connected at 227 to a clevis 228 (see Fig. 4) which at its lower end, carries a clevis 229 (see Fig. 2) fitting over the pin 230 when the beam M and latch H are in normal operating position as indicated in Figs. 2, 3 and 4.

It will be noted that the pin 230 is provided with an upper knife edge and is connected to the forward end of the beam M. The beam 222 is provided with a weight 231 which may be variably located by the screw 232 at varying positions on the beam 222 to compensate the amount of material being weighed out which is included in the falling column in air. The beam 222 is provided with a forward extension 233 carrying the round element 234, which serves as a hand grip.

It will be noted in referring to Figs. 8 and 9 that the scale beam N is provided with a bar element 235 which is connected at 236 to an extension 237 on the beam N and carries an adjustable weight 238, which may be fixed in position by the lock screw 239. The weight 238 (Figs. 8 and 9) and the bar element 235 are used to correct for changes in the weight or balance of the structures E, F and G.

Upon the front portion of the longitudinal frame member 20 is connected a plate 240 (see Fig. 1) by the bolts 241, said plate having an upstanding arm 242 with an inside pointer 244 cooperating with the graduations 245 on the front of the hanger 70 by means of which it is possible to gauge whether the scale is in balance, graduations 245, if desired, being graduated to indi-

cate when the scale is in balance, whether it is balanced too light or too heavy.

When the bag held on the structure E and gripped between the jaws 115 and the forward ends of the arms 101, has received its predetermined weight and it is desired to check the balance, by grasping and elevating the elements 234 and 44 respectively at the right and left hand sides of the weighing machine structure as indicated in Fig. 1, it is possible to unlatch the structure H as shown in Figs. 4 and 5, and I as shown in Figs. 8 and 9, thus releasing gates K and L, from the beam structure M and N. Elevating the hand grip 234 through the finger 218 will elevate and move the swinging element 82, outwardly as shown in Fig. 5, thus disengaging the roller 83 from the surface 216a. At the same time, by moving the hand gripped portion 44 upwardly as shown in Figs. 8 and 9, the foot 47 will be moved outwardly out of the path of the foot 49. At this point, it is possible for the structure E to move upwardly and downwardly and balance against the structure C with the gates K and L remaining closed as indicated in Figs. 3 and 8.

At the same time, the pointer 244 will assume the desired position in respect to the graduations 245, indicating whether the balance is correct or is too heavy or too light, in which case correction may be made by the moving adjustable weight 231 (see Fig. 3).

When the balance has then been checked, the release of the handle 44 will permit the arm 46 and the foot 47 to fall back into normal position as shown in Figs. 8 and 9.

However, the lower end of the swinging latch 82 normally rides quite closely to the roller 83 throughout the movement of the scale beam M, and in the balancing position the roller 83 will move to a higher position than the bottom surface 216a of the latch 82, as indicated in Fig. 5.

In this case, when the latch 82 is permitted to drop, it is necessary that its lower face 216a be located above the roller 83, as shown in Fig. 4 and this is accomplished by depression of the forward end of the scale beam M by the clevis 229 bearing downwardly on the pin 230.

In Figs. 13 and 14 is shown an alternative construction, correspondingly functioning parts as in Figs. 1 to 12 being indicated by the same numerals primed. In the construction of Figs. 13 and 14, is shown an expander element 400 which is designed to receive the rear of the bag and hold same extended when the upper forward edges of the bag are gripped by the clamping structure F'. This structure 400 is connected to the bracket 199' by the flange 401 and the rivets 402, and if desired, the connections 402 may be detachable to permit removal of the element 400 at any time.

The element 400 takes up extra slack in the bag and also relieves the arms 101 from taking up excessive amounts of slack where large bags are utilized. By utilizing elements such as 400, it is possible to accommodate the spout E and the clamping structure F to a wide variety of different sizes and shapes of bags.

Referring to Figs. 15 and 16, similarly functioning parts being indicated again by the same numerals as in Figs. 1 to 12, which numerals are primed, the jaws 115' are supported as previously described upon arms 114' except that the pivot pin 129' fits in a slot 403 in the arm 114' and the slots 127' are enlarged as indicated at 404 to receive the enlarged portions 405 of the

arms which receive the coil springs 406, said coil springs being adjusted by means of the screws 407. This resilient construction 406 enables better adjustment of the pivotally mounted jaws 115' in respect to the rails 135' and the springs 406 will take up any variation in clamping between the jaws 115' and the rails 135'.

In the construction shown in Fig. 17, to replace links as shown in Fig. 10, similarly functioning parts being indicated by the same numerals and letters primed, the sleeve 104' receives the spring 410 which reacts against the nut 411 on the bolt 412. The shank 102' is unthreaded and extends into said sleeve 104'. The other element 103' may be of the same construction and manner of operation as the element 103 already described, shown in connection with Fig. 10.

It is thus apparent that the present applicant not only has provided a convenient arrangement for holding the bag without crumpling of the upper end thereof, and with assurance that the slack of the bag will be firmly gripped, but in addition has provided a simple latching arrangement by means of which a trial balance may be had when the bag has received its predetermined charge. Both the bag holding structure F and G and the latching structure H and I may be conveniently assembled or placed upon machines already sold or in usage, without substantial reconstruction or expense.

The invention, however, is not intended to be restricted to any particular construction or arrangement of parts, or to any particular application of any such construction, or to any specific method of operation, or manner of use, or to any of various details thereof, herein shown and described, as the same may be modified in various particulars or be applied in many varied relations without departing from the spirit and scope of the claimed invention, the practical embodiments herein illustrated and described merely showing some of the various features entering into the application of the invention.

What is claimed is:

1. In a machine of the type having a spout designed to hold a bag to receive a predetermined charge of material, means to clamp said bag on said spout comprising two fixed arcuate clamping jaws on the sides of the spout, two movable arcuate clamping jaws to be moved sidewardly toward or away from said fixed jaws, a pair of arms carrying said jaws, a pivotal mount for said arms at the rear of the spout and an actuating arrangement having a supplemental pair of jaws to take up any slack in said bag at the front of said spout, said movable jaws being pivotally mounted on said arms.

2. In a machine of the type having a spout designed to hold a bag to receive a predetermined charge of material, means to clamp said bag on said spout comprising two fixed arcuate clamping jaws on the sides of the spout, two movable arcuate clamping jaws to be moved toward or away from said fixed jaws, a pair of primary arms carrying said jaws, pivotal and resilient connections between said arms and said jaws, a pivotal mount for said primary arms at the rear of the spout and an actuating arrangement at the front of said spout, said actuating arrangement including adjustable rods pivotally connected to the front ends of said arms and secondary arms rotatably mounted at one side on said spout and at the other side being connected to the ends of the adjustable rods.

3. In a machine of the type having a spout designed to hold a bag to receive a predetermined charge of material, means to clamp said bag on said spout comprising two fixed arcuate clamping jaws on the sides of the spout, two movable arcuate clamping jaws to be moved toward or away from said fixed jaws, a pair of arms carrying said jaws, a pivotal mount for said arms at the rear of the spout and an actuating arrangement at the front of said spout, said movable jaws being provided with slots on both faces to receive said arms and fixed jaws.

4. In a machine of the type having a spout designed to hold a bag to receive a predetermined charge of material, means to clamp said bag on said spout comprising means to clamp the body of the bag and means to clamp any slack in said bag, each of said two last-mentioned means comprising pairs of levers pivotally mounted on opposite sides of said spout.

5. In a machine of the type having a spout designed to hold a bag to receive a predetermined charge of material, means to clamp said bag on said spout comprising a pair of primary movable jaws to clamp the upper end of the bag to the bottom of the spout and a pair of secondary jaws to take up any slack in the bag and actuating means to close said primary jaws before closing said secondary jaws.

6. In a machine of the type having a spout designed to hold a bag to receive a predetermined charge of material, means to clamp said bag on said spout comprising means to clamp the body of the bag and means to clamp any slack in said bag, each of said two last-mentioned means comprising pairs of levers pivotally mounted on opposite sides of said spout, and linkages connecting the forward ends of said pairs of levers, whereby they are caused to move together and apart in unison.

7. In a machine of the type having a spout designed to hold a bag to receive a predetermined charge of material, means to clamp said bag on said spout comprising two fixed arcuate clamping jaws on the sides of the spout, two movable arcuate clamping jaws to be moved toward or away from said fixed jaws, a pair of arms carrying said jaws, a common pivotal mount for said arms at the rear of the spout, biasing means to move said arms apart located at the rear of the spout and an actuating arrangement at the front of said spout, said actuating arrangement including linkages connected to the front ends of said arms, levers connected to the ends of

said linkages, and means for operating said levers to move said clamping jaws toward and away from said fixed jaws.

8. In a machine of the type having a spout 5 designed to hold a bag to receive a predetermined charge of material, means to clamp said bag on said spout comprising two fixed arcuate clamping jaws on the sides of the spout, two movable arcuate clamping jaws to be moved toward or away from said fixed jaws, a pair of arms carrying said jaws, a pivotal mount for said arms at the rear of the spout and an actuating arrangement at the front of said spout, said movable jaws being centrally pivotally mounted on said arms and said movable jaws being provided with recesses in which said arms are received and being further provided with guiding pads adjacent said ends to permit them to swing with alignment on said central pivotal 10 mounts.

9. In a machine of the type having a spout 15 designed to hold a bag to receive a predetermined charge of material, means to clamp said bag on said spout comprising means to clamp the body of the bag, means to clamp any slack in said bag, each of said two last-mentioned means having clamping jaws and means to operate both said clamping means together and apart in unison.

10. In a machine of the type having a spout 20 designed to hold a bag to receive a predetermined charge of material, means to clamp said bag on said spout comprising means to clamp the body of the bag, means to clamp any slack in said bag, each of said two last-mentioned means having clamping jaws and means to operate both said clamping means together and apart in unison, said clamping means being connected to operate together by adjustable link means whereby 25 said operating means will cause said first mentioned clamping means to clamp the bag upon the spout and then said second mentioned clamping means to clamp any slack in said bag.

11. In a machine of the type having a spout 30 designed to hold a bag to receive a predetermined charge of material, means to clamp said bag on said spout comprising means to clamp the body of the bag, means to clamp any slack in said bag, each of said two last-mentioned means having clamping jaws and means to operate both said clamping means together and apart in unison, and biasing means to bias said clamping 35 means to open position.

PETER HANNAH.
